Wooking Stoves and Ranges.

No. 12,092

JANUARY 4, 1881

UNITED STATES PATENT OFFICE.

H. CLAY BASCOM AND FRANCIS RITCHIE, OF TROY, NEW YORK, ASSIGNEES
TO THE N. S. VEDDER PATTERN WORKS, BASCOM, GALBRAITH & CO.,
OF SAME PLACE.

DESIGN FOR A STOVE.

SPECIFICATION forming part of Design No. 12,092, dated January 4, 1881.

Application filed November 24, 1880. Term of patent 3½ years.

To all whom it may concern:

Be it known that we, H. CLAY BASCOM and FRANCIS RITCHIE, each of the city of Troy, in the county of Rensselaer and State of New York, have jointly invented a new and original ornamental Design for Cooking-Stoves and Ranges, of which the following is a specification, reference being had to the accompanying cut, print, or engraving.

10 The design for the upper shelf-brackets, A A, consists of the two reversely-arranged parts B B, connected by the band a, and having the outer ovolo-cavetto border, b, the panel c, having the sides d d' straight and at right angles, and the other side, d'', of ovolo-cavetto form, and the cruciform ornament e on said panel, with the two trifid ornaments f f' extending perpendicularly and laterally from two adjacent angles of said cruciform ornament, and the 15 whole being shaped and disposed substantially as represented in the accompanying print.

15 The design for the ventilator-pipe C consists of the circular ornamented projecting part D, and the upper and lower panels, g g, each having the central cruciform ornament, h, with the two laterally-extending three-cleft ornaments i i', all shaped and arranged together so as to 20 present the appearance represented in the accompanying cut.

20 The design for the panel ornament E consists of the oblong rectangular tablet j, having the plaid-checked surface, and the rectangular fillet-border k, having the in-cut obtuse-angled 25 outwardly-projecting inclined parts l l' at the ends and sides, and all shaped and arranged together as shown in the accompanying engraving.

25 The design for the panel ornament F consists of the rectangular sub-panel m, having thereon the cruciform ornament n, with the trifid ornaments n' extending from its angles, and the rectangular fillet-border o, with the in-cut obtusely-inclined ornaments p projecting 30 outward from all sides of said fillet-border, all of said parts being shaped and arranged together in combination so as to present the appearance represented in the aforesaid engraving.

The design for the panel-border of the doors 50 consists of the particular compound bar-and-ball-ornamented outer molding, s, in combination with the inner in-cut corner ornaments, t, each having the two outer lancet-shaped arms, t', and the three branched end-expanded arms 55 t'', all shaped and arranged together upon and around the rectangular panel-surface of the door, as shown in the aforesaid print, with or without in-cut linear side ornaments, u, between the said corner ornaments.

60 The design for the large doors G H consists of the compound ornament E and ornamental border s t u, all shaped and composed as above specified, and combined and arranged on and around the panel-surface r, as represented in 65 the aforesaid engraving.

The design for the small doors or panels I J K L consists of the compound ornament F and ornamental border s t, each composed and shaped as above specified, and all arranged together on and around the rectangular panel-surface q, as shown in the aforesaid print.

70 The design for the rear side plate consists of the reversely-curved lower border, M, and the panel N, of triangular form, with plaid-checked surface, having thereon the cross v and three-cleft ornaments v', and surrounded by the peculiar bar-and-ball-ornamented fillet having the two straight sides w w' and reversely-curved side w'', all shaped and arranged 75 together as shown in the aforesaid cut.

75 The design for the end door consists of the oblong rectangular upper section, O, having the bar-and-ball-ornamented border-frame x, inclosing the series of quadrilateral illumination-apertures x', having their upper corners concave and the intermediate ornamented bars, x'', the projecting lower section, P, having the series of smaller rectangular apertures y, with the intervening and lateral ornamented 80 panels y', and the middle inclined section, Q, having the raised oblong rectangular panel z, all shaped and arranged together as shown in the aforesaid engraving.

85 The design for the legs consists of the lower central rectangular panel, R, having therein the cross-ornament R', the lower lateral panels, S S, inclined to the panel R and having orna-

mental outer borders, the central rectangular upper panel, T, and lateral inclined panels U U, having basket-work surfaces, the whole being shaped and combined as shown in the 5 print.

What we claim as our invention is—

1. The design for the upper shelf-brackets, A A, consisting of the parts B B a b c d d' d² e f f, all shaped and arranged together as set 10 forth.
2. The design for the pipe C, composed of the parts D g g h i i, all shaped and combined as set forth.
3. The design for the panel ornament E, composed of the parts j k l l', all shaped and combined as shown and described.
4. The design of the panel ornament F, composed of the parts m n n' o p, all shaped and combined as described and shown.
5. The design for the panel-borders of the doors, composed of the parts s t t' t², all shaped and arranged together upon the panel-surface as shown and described.
6. The design for the large door G, com-

posed of the parts E, s t u, and r, all shaped 25 and arranged together as shown and described.

7. The design for the small doors or panels I J K L, composed of the parts F s t q, all shaped and arranged together as shown and described.

8. The design for the rear side plate, composed of the parts M N v v' w w' w², all shaped and arranged together as set forth.

9. The design for the end door, consisting of the parts O x x' x² P y y' Q z, all shaped 35 and arranged together as shown and described.

10. The design for the legs, consisting of the parts R R' S S T U U, all shaped and arranged in combination as described and shown.

In testimony whereof we hereunto set our 40 hands, in the presence of two subscribing witnesses, this 22d day of November, 1880.

H. CLAY BASCOM,
FRANCIS RITCHIE.

Witnesses:

JAMES A. GILMAN,
CHESTER BASCOM.
